(57) **CLAIM**

The ornamental design for a shin-shaped menorah, as shown and described.

DESCRIPTION

FIG. 1 is a rear view of a shin-shaped menorah showing my new design;

FIG. 2 is a front view thereof;

FIG. 3 is a right view thereof;

FIG. 4 is a left view thereof;

FIG. 5 is a top plan view thereof;

FIG. 6 is a bottom plan view thereof; and,

FIG. 7 is a perspective view thereof.

The broken line showing star and writing is included for the purpose of illustrating environmental structure and forms no part of the claimed design.
